UNITED STATES PATENT OFFICE.

HUGO WITTMAN, OF BUFFALO, NEW YORK.

BUILDING BLOCK AND WALL CONSTRUCTION.

Application filed April 25, 1927. Serial No. 186,228.

This invention relates to hollow building blocks of the kind which are adapted to co-operate or interlock with bricks to form a wall built of both brick and blocks, and to wall constructions involving the use of these blocks.

In building blocks or hollow tile as heretofore made the shapes of the blocks have generally been such that blocks of several sizes or shapes were necessary to construct any wall, or else the blocks were so made that the wall construction necessitated the use of an odd shaped brick or a split brick to start the wall construction in a horizontal plane, or to finish the wall construction at its upper end in a horizontal plane.

The objects of this invention are to provide a building block of this kind which is of such construction that only a single size or shape of block is necessary for use in constructing a wall and which is so formed that the building block and brick at the base and top of the wall may be laid in horizontal planes, thus eliminating the use of slabs or other inserts or of splitting or breaking blocks or bricks; also to provide a building block which can be made of convenient sizes and which is shaped so that it can be easily picked up and handled; also to provide a building block of this kind which is constructed with a plurality of horizontal air cells and in which the walls between the cells as well as the outer walls of the block are shaped to be in vertical alinement with the corresponding walls of adjacent building blocks and which walls are also formed to lie in alinement with the ends of interlocking bricks in the construction of a wall made of brick and blocks; also to improve the construction of building blocks of this kind and of wall constructions in other respects hereinafter specified.

In the accompanying drawings,

Fig. 1 is a cross sectional elevation of a wall construction in which a building block embodying my invention is employed.

Fig. 2 is a perspective view of the building block.

Fig. 3 is a cross sectional elevation of the wall of slightly modified construction.

The building block or tile A shown in Figs. 1 and 2 is of L-shaped or angle shaped cross section, one side of the block being of greater height than the other side, and the heights of the two sides of the block may vary depending upon the number of courses

of bricks which are to be laid between interlocking courses. However, in accordance with my invention, the difference in height between the two sides of the block must always be equal to the height of a brick and a mortar joint. The blocks may be provided with a plurality of upright walls or webs, including a long outer wall 6 and a shorter outer wall 7, an intermediate long wall 8, and preferably a short intermediate wall 9,

60 which two walls are spaced apart so as to form between them an air space or cell 10. The top and bottom walls 11 and 12 of the long side of the block, joining the upper and lower ends of the walls 6 and 8, form between them a horizontal air space or cell 13, and the top and bottom walls 14 and 15 respectively of the portion of the block of less height, form with the upright walls 7 and 9 65 an air space 16. The wall 14 preferably extends to the upright wall 8 so that the portion 17 thereof forms a connection between the two sides of the block, and the other wall 15 may also be so formed as to be a continuation of the wall 12, or if desired the two walls 12 and 15 may be interrupted to form a longitudinal groove 18 which may be utilized to form an interruption in the mortar joint, and a short wall 19 may be used to 70 connect the two walls 8 and 9 to form therewith and with the wall or web 17 the air space 10, the wall 19 being offset with reference to the two horizontal walls 12 and 15, which lie in substantially the same plane. 75

By means of this arrangement three horizontal air cells are provided in the block and the walls 6 and 8 are spaced apart a distance equal to the spacing between the walls 7 and 9, so that when one block is placed upon another block in an inverted position as clearly shown in Fig. 1, the walls 7 and 9 of one block will be in alinement with the walls 6 and 8 of the other block. The distance between the walls 7 and 9 is preferably also

80 such that when the blocks are used in a wall construction such as shown in Fig. 1, in connection with a series of courses of bricks B and a course of bonding bricks C, the inner portions of the bonding bricks will lie over 85 the upright partition or wall 9 of an adjacent block. If desired the sides of the block which are to be plastered or to which mortar is to be applied may be scored in any suitable or desired manner and may, for example, be provided with grooves 20 of any suitable kind. The building block may be 90 95 100 105 110

made of any suitable material, such, for example, as burnt clay.

- In the construction of a wall such as shown in Fig. 1, the blocks are laid in such a manner that alternate blocks are inverted and also alternated or reversed side for side, so that if one block is laid with its higher side adjacent to the inner side of the wall, the next adjacent blocks above and below the same are arranged with their lower sides adjacent to the inner face of the wall. In the wall as shown five courses of bricks B are laid in the usual manner and the sixth course is provided with bonding bricks C, the inner ends of which extend into the space between the low side of a block and the high side thereof. In the particular construction it will be noted that the heights of two of the high sides of a block and one low side and their mortar beds or joints D is equal to the height of six courses of bricks and their mortar joints D, and similarly the heights of two low sides of the blocks and one high side together with their mortar joints is equal to the height of five courses of bricks and their mortar joints, the sixth course of brick and one mortar joint being equal to the difference in height between a low side and a high side of a block. In other words, three courses of blocks with their mortar joints are equal in height to the height of the number of courses of brick between bonding courses and a bonding course together with their mortar joints. If the wall is to be constructed with a different number of courses of bricks between the bonding courses, my improved blocks are so constructed that the height of two long sides of the blocks and one short side, together with their mortar joints is equal to the height of the number of courses of brick between the bonding courses, plus the bonding courses and the necessary mortar joints between courses. Each of the blocks, however, regardless of size, is so constructed that the difference in height between the high side and the low side of the block is equal to the height of a course of brick and one mortar joint. It will be obvious too that these blocks may be used for constructing a wall without face brick by simply inverting alternately each block and turning them so that their high and low sides are arranged alternately at opposite sides of the wall.
- In the particular construction shown in Fig. 3, a slightly different arrangement of the blocks with reference to the brick is shown. In this construction the lowest block is arranged with its higher side adjacent to the brick and with its lower side at the inner face of the wall. The next block is inverted and reversed side for side, and the third block is merely inverted without reversing the same side for side.
- In either of the constructions shown in

Fig. 1 or in Fig. 3, the building of the wall can be started on a horizontal surface without the use of slabs or split brick under a portion of the wall. An important advantage in the wall construction resulting from the use of these blocks is that the inner edges of the bonding bricks C lie over and are supported by the vertically aligned walls or webs 9 and 8 of the block, so that a stronger wall results than is formed if the bonding bricks stop short of the aligned webs 8 and 9. Furthermore the mortar joints are all interrupted in such a manner that no mortar joint extends completely from the outer face of the wall to the inner face, so that no moisture from the outer wall can penetrate through to the inner wall due to the capillary attraction or hygroscopic nature of the mortar. When the blocks are arranged in a wall as shown in Figs. 1 and 3, three complete series of horizontal air cells are provided between the longitudinally laid brick courses B and the inner face of the wall, and two air cells between the bonding brick and the inner face of the wall. The webs which are arranged between the air cells and which constitute the side walls of the block are so arranged that they are in vertical alignment with webs of adjacent blocks so that an unusually strong wall is produced. The individual blocks are of such size that they can be very easily handled in the building of a wall, the portion of the side of each block of lesser height being such that it can be readily grasped by the hand and the thickness or width of the portion of greater height being such that this portion can also be grasped by the hand, and the recess or groove between the walls 8 and 9 also affords an additional grip. These features of the block make it possible to build a wall at greater speed and efficiency.

I claim as my invention:

1. A hollow building block provided with two sides of unequal height, one horizontal wall of one side lying in substantially the same plane as the corresponding wall of the other side, and the other horizontal walls of the two sides lying in planes which are spaced apart a distance equal to the height of a brick and a mortar bed, and of less height than the height of two bricks and a mortar bed the side of less height being of greater height than the height of a brick and a mortar bed.

2. A wall construction including face brick laid with a bonding course between a definite number of other courses, and hollow angle-shaped building blocks laid vertically on the inner face of said face brick and bonded therewith, each of said blocks including a low side and a high side, the difference in height between said sides being equal to the height of a brick and a mortar bed, said blocks being laid so that one high side and

two low sides are arranged vertically below each course of bonding brick, and so that two high sides and one low side are arranged in vertical alinement on the inner face of the wall, the height of said low side being of greater height than the height of a brick and a mortar bed and of less height than the height of two bricks and a mortar bed.

3. A wall construction including face brick laid with a bonding course between a number of other courses, and hollow angle-shaped building blocks laid vertically in courses on the inner side of said face brick, each block having two sides of different heights, the difference in height being equal to the height of a brick and a mortar bed, each of said sides being formed by a pair of upright webs connected by horizontal webs, and webs connecting said sides and forming a horizontal air space between said sides, said blocks being laid in three courses between each course of bonding brick, the blocks of said two lower courses being so arranged that the blocks of one course are inverted and reversed side for side with reference to the blocks of the other course, and the blocks of the third course being arranged with their low side beneath the portion of said bonding course of brick extending inwardly beyond said other course, the vertical webs of each course of blocks being in vertical alinement with other courses of blocks and at least two vertical webs of all of said blocks being arranged entirely beneath the bonding bricks.

4. A wall construction including face brick laid with a bonding course between a number of other courses, and hollow angle-shaped building blocks laid vertically in courses on the inner side of said face brick, each block having two sides of different heights, the difference in height being equal to the height of a brick and a mortar bed, each of said sides being formed by a pair of upright webs connected by horizontal webs, and webs connecting said sides and

forming a horizontal air space between said sides, said blocks being laid in courses between each course of bonding brick, the upright webs of each side of the blocks being spaced apart so that when a side of a block is arranged below a bonding course, the inner edge portion of the bonding brick will lie completely over the web of said side of the block nearest to the other side of the block, the low side of each block being of greater height than the combined height of a brick and a mortar bed and of less height than the height of two bricks and a mortar bed.

5. A hollow building block provided with two sides of unequal height, one horizontal wall of one side lying in substantially the same plane as the corresponding wall of the other side, and the other horizontal walls of the two sides lying in planes which are spaced apart a distance equal to the height of a brick and a mortar bed, said two sides being of equal width and the side of less height being of greater height than the combined height of a brick and mortar bed and of less height than the height of two bricks and a mortar bed, said sides being connected by webs.

6. A hollow building block provided with two sides of unequal height, one horizontal wall of one side lying in substantially the same plane as the corresponding wall of the other side, and the other horizontal walls of the two sides lying in planes which are spaced apart a distance equal to the height of a brick and a mortar bed, the side of less height being of greater height than the height of a brick and a mortar bed and of less height than the height of two bricks and a mortar bed, said sides having a series of vertical webs, the side walls of each of which is in alinement with the corresponding side walls of vertical webs of a similar superimposed inverted block reversed side for side with said first mentioned block.
